United States Patent Office.

L. H. ALLEN AND JOHN B. WILFORD, OF TAMAQUA, PENNSYLVANIA.

Letters Patent No. 80,698, dated August 4, 1868.

IMPROVEMENT IN STEAM-ENGINE SLIDE-VALVES.

The Schedule referred to in these Letters Patent and making part of the same.

TO ALL WHOM IT MAY CONCERN:

Be it known that we, L. H. ALLEN and JOHN B. WILFORD, of Tamaqua, in the county of Schuylkill, and State of Pennsylvania, have invented a new and useful Improvement in Steam-Valves and Valve-Motion; and we do hereby declare that the following is a full, clear, and exact description thereof, which will enable those skilled in the art to make and use the same, reference being had to the accompanying drawings, forming part of this specification.

This invention relates to an improvement in sliding steam-valves, and to the method by which they are operated; and it consists in the arrangement of the bars formed upon the slide-valve, with the exhaust-openings and passages, whereby the stroke of the valve is completed, so as to make the maximum opening of the ports, as will be hereinafter described.

Figure 1 is a horizontal section of the face of the main cylinder, and of the auxiliary cylinder, showing the apertures through which the exhaust steam passes from the main cylinder to the auxiliary cylinder, also the steam and exhaust-ports, the section being through the line *z z* of fig. 2, with the valve removed.

Figure 2 is a vertical section of fig. 3, through the line *y y*.

Figure 3 is a longitudinal vertical section through the line *z z* of fig. 1.

Similar letters of reference indicate corresponding parts.

A is the main or engine-cylinder.

B is the auxiliary cylinder.

C is the slide-valve.

D is the steam-chest.

E is a piston in the auxiliary cylinder, the rod of which, F, is attached to one end of a vibrating-lever, G, which lever is pivoted to a stand on the main cylinder, as seen at *h*.

The valve-rod, J, is attached to the other end of G.

i i are the apertures for the passage of the steam from the main cylinder A to B.

K represents the steam-ports, and

L the exhaust-ports of the engine.

The valve is operated by steam, which passes from the main cylinder through the apertures *i*, and drives the piston E one way or the other at the completion of each stroke.

The vibrating-lever G will cause the valve to be reversed, when the passage *i* will be closed, and the piston E will cushion on the back steam.

The bars, *m m*, on the face of the valve, will close the exhaust-ports until the exhaust steam has acted on the piston E and moved the valve, as described.

This improvement is designed more particularly for pumping-engines, but it is applicable to other engines. It will be observed that none but exhaust steam is used in the auxiliary cylinder, so that there can be no loss of power by this method of operating the valve.

We are aware of the patents granted to W. C. Wicks, for improvement in slide-valves, dated January 9, 1855, and George F. Blake, for improvements in direct-acting engines, and for improvements in steam-engines, dated, respectively, January 1, 1867, and April 12, 1864, but as these patents do not show our arrangement of devices, they form no part of our invention; but

We claim as new, and desire to secure by Letters Patent—

The arrangement of the bars *m m* with the exhaust-openings L L and passages *i i*, whereby to complete the stroke of the valve C, so as to make the maximum opening of the ports, substantially as set forth.

L. H. ALLEN,
JOHN B. WILFORD.
